UNITED STATES PATENT OFFICE.

LUDWIG G. WIDLAK, OF NEWARK, NEW JERSEY, ASSIGNOR TO ROSENBAND MANUFACTURING CO., A CORPORATION OF NEW JERSEY.

BAG OR PURSE FRAME.

1,281,731.

Specification of Letters Patent. Patented Oct. 15, 1918.

Application filed April 17, 1917. Serial No. 162,622.

To all whom it may concern:

Be it known that I, LUDWIG G. WIDLAK, a citizen of the United States, residing at Newark, in the county of Essex and State of New Jersey, have invented certain new and useful Improvements in Bag or Purse Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in bag-frames, and the like; and, the present invention has reference, more particularly, to an improved bag, or purse - frame, comprising usually three-frame-sections, two of which are connected with each other at their ends by means of pivot-pins, and the third frame-section being pivotally connected, so as to be reversible with the other two frame-sections, by means of pivot-plates with the pivot-pins of the said two frame-sections.

The present invention has for its principal object to provide in connection with the pivotal means of connection of the three frame-sections of a reversible bag or purse-frame, means coöperating with the third and reversibly disposed frame - section, whereby the said reversible frame-section, no matter in which final position, either upon the front or the back of the two main and pivotally connected frame-sections, will always be in perfect registration with said two main frame-sections.

Other objects of the present invention not at this time more particularly enumerated will be clearly understood from the following detailed description of the present invention.

With the various objects of the present invention in view, the said invention consists, primarily, in the novel reversible bag or purse-frame and frame-section registration means therefor; and, the invention consists, furthermore, in the several novel arrangements and combinations of the various parts, as well as in the details of the construction of the same, all of which will be more fully

described in the following specification and then finally embodied in the clauses of the claim which are appended to and which form an essential part of the said specification.

The invention is clearly illustrated in the accompanying drawings, in which:

Figure 1 is a front elevation of a bag or purse - frame comprising two main frame-sections, and a third and reversibly disposed frame-section hingedly connected in the manner of the present invention and provided at the hinge-connections with a frame - registering means, showing one embodiment of the principles of the present invention; and Fig. 2 is an end view of the bag or purse-frame.

Fig. 3 is a detail sectional representation of the three frame-sections, said section being taken on line 3—3 in said Fig. 1, looking in the direction of the arrow *y*; Fig. 4 is a similar sectional representation of the same parts, showing the reversible frame-section being turned from its position indicated in said Fig. 3 in the direction of the arrow *z*; and Fig. 5 also is a similar sectional representation showing the third and reversible frame-section rotated into its reversed relation with the two main frame-sections.

Fig. 6 is a horizontal section, said section being taken on line 6—6 in said Fig. 2, and said view being made on an enlarged scale; and Fig. 7 is a transverse vertical section, taken on line 7—7 in said Fig. 1, looking in the direction of the arrow *x*.

Fig. 8 is an end view of a fragmentary part of a three-part reversible frame, showing a slightly modified construction of 90 hinged or pivotal connection in which the outer link-plate is dispensed with.

Fig. 9 is a view similar to that shown in Fig. 8, of a three-part reversible frame, the frame-sections being provided with another 95 form of frame-registering means, and Fig. 10 is a view of the same parts represented in said Fig. 9, but showing the third and reversible frame-section being rotated into its reversed relation with the two main frame-sections.

Fig. 11 is an end elevation of one of the hinged end-portions of a reversible bag-frame, in which the frame-sections are piv-

totally connected by means of hinge-devices riveted to the end-portions of the respective frame-sections, the hinge-devices in this instance being provided with frame-registering means embodying the principles of the present invention.

Fig. 12 is an outer face end view, and Fig. 13 an inner face end view of a four-part bag-frame, showing one of the hinged ends 10 of the bag-frame provided with a registering means, similar to that illustrated in Figs. 1 to 7 inclusive.

Fig. 14 is an end view, and Fig. 15 a top view of one of the hinged or pivoted end-15 portions of a reversible three-part bag-frame, provided with still another modified registering means for bringing the third and reversible frame-section into perfect registration upon either side of the two main 20 frame-sections of the bag-frame.

Similar characters of reference are employed in all of the said above described views, to indicate corresponding parts.

Referring now to the said drawings the 25 reference character 1 indicates a complete bag frame, comprising a frame-section 2 and a frame-section 3 each provided at their ends, with perforated ears 4. The perforated ears of said frame-section 2 coöperate 30 or register with the perforated ears of said frame-section 3, so that a pivot-pin or rivet 5 may be passed therethrough to pivotally connect said frame-sections together. The reference character 6 indicates a reversible 35 frame-section adapted to be connected with said frame-sections 2 and 3, so that it may be turned around to position the same selectively either on one side or the other of said frame-sections 2 and 3. This is accomplished by means of hinge-links 7, one end 40 of each hinge-link being pivotally journaled on the pivot-pin or rivet 5 of said pivotally connected frame-sections 2 and 3, and the other end of each hinge-link being pivotally 45 secured to the perforated ears 8 of said reversible frame-section 6 by means of a pivot-pin or rivet 9. It will, of course, be apparent that by thus providing said reversible frame-section 6 in connection with the pivotally 50 connected frame-sections 2 and 3, the complete bag-frame is adapted to support, a reversible bag-body which may be turned inside out at will, to expose one of its two ornamental sides of varying designs, material or color, all of which is old and well known in the art.

In connection with the two main frame-sections 2 and 3, and the third and reversibly disposed frame-section 6 hinged or pivoted in substantially the manner hereinabove set forth, the respective frame-sections are provided with suitably constructed latch or catch-devices, as 10, 11, 12 and 13, 60 which may be of the construction set forth in my former application for Letters-Pat- 65

ent, filed September 15th, 1916, Serial No. 120,209/15; or, said latch or catch-devices may be of any other suitable constructions, as will be clearly evident.

The alining or registering means for 70 properly positioning the reversible frame-section 6 in perfect registration upon either side of the closed main frame-sections 2 and 3, consists, essentially of suitably shaped link-plates, as 14, each plate being provided 75 with suitably disposed holes or perforations for pivotally mounting the said plates, firstly, upon the pivot-pins or rivets 5, and, secondly upon the pivot-pins or rivets 9, whereby said link-plates are capable of rotary or turning action upon said pivot-pins or rivets 5 and also upon the pivot-pins or rivets 9, so as to permit of a complete rotary movement of the frame-section 6 from its one position upon the closed frame-sections 80 2 and 3, indicated in said Fig. 3 of the drawings, to its reversed position upon and against the frame-section 3, as clearly shown in Fig. 5 of the drawings.

As shown, each link-plate 14 is preferably 90 curved at its ends, as at 15 and 16, but the longitudinally extending and connecting marginal edges 17 and 18 are made straight, so that when the parts are in the positions indicated in said Fig. 3, the straight edge 95 17 will suitably abut against the ends 20 of the members 19 of the various frame-sections 2, 3 and 6, and when in the positions indicated in said Fig. 5, then the other straight edge 18 will suitably abut against the said 100 ends 20 of the members 19 of the respective frame-sections, as shown. Thus, it will be clearly seen, that by means of these link-plates, and their coöperation with the respective frame-sections, no distorted pivotal 105 relation of the various parts will result at the hinge-connections of the frame-sections, and an alining or registered means is the result which will always bring the reversible frame-section 6 into perfect registration, 110 either with the frame-section 2 or with the frame-section 3, according to its position upon either side of the two closed main frame-sections 2 and 3.

If desired, a washer, as 21, may be disposed upon the pivot-pins or rivets 9, between the link-plates 14 and the ears 8 of the said frame-section 6, as indicated in Fig. 6 of the drawings, but said washers are not essential and may be dispensed with if 120 desired.

In the construction represented in Fig. 8 of the drawings, the two main frame-sections are indicated by the reference-characters 22 and 23, the said frame-sections being 125 pivotally connected by means of rivets 24 at their respective end-portions. The reference-character 25 indicates the third and reversible frame-section which is provided with a rivet 26. Mounted upon the said rivet 130

ets 24 and 26 in the manner of the previously described alining or registering means, is a link-plate 27, the additional link-plate 7, employed in the construction represented in 5 said Figs. 1 to 7 inclusive being dispensed with. In all other respects the operation for producing the perfect alinement or registration of the several frame-sections is the same as that described in connection with 10 the construction shown in said Figs. 1 to 7 inclusive.

In the modified construction illustrated in Figs. 9 and 10 of the drawings, the reference-characters 28 and 29 indicate two main 15 frame-sections provided at their ends with perforated ears 30, and pivotally connected by means of a pivot-pin or rivet 31. The reference-character 32 indicates the third reversible frame-section which is connected 20 with said main frame-sections 28 and 29, so that it may be turned around to position the same selectively either on one side or the other of said frame-sections 28 and 29, by means of a hinge-link or plate, as 33, one 25 end-portion of said link or plate 33 being journaled upon the pivot-post or pin 31, and the other end-portion of said link or plate being pivotally mounted upon a pivot-post or pin 34 with which the reversible frame- 30 section 32 is provided.

The alining or registering means for properly positioning the reversible frame-section 32 in perfect registration upon either side of the closed main frame-sections 35 28 and 29 consists of laterally and slightly outwardly projecting lugs or extensions, as 35 and 36, against which the respective marginal edge-portions 37 and 38 can be made to abut, as will be clearly evident, so 40 as to provide for the perfect alinement or registration of the respective frame-sections, as will be clearly understood from an inspection of said Figs. 9 and 10.

In some cases the end-portions of the 45 frame-sections 39 and 40, and the reversible frame-section 41, may be cut off straight, as indicated in Fig. 11 of the drawings, the two main frame-sections 39 and 40 having secured thereto by means of rivets 42, or 50 otherwise, suitable hinge-members, as 43 and 44, provided with registering and perforated pivot-ears 45, pivotally connected by means of a pivot-post or rivet 46. The third and reversible frame-section 41 has also secured 55 thereto, by means of rivets 47, or otherwise, a hinge-member 48, provided with an ear or extension 49, carrying a pivot-post or rivet 50. Journaled upon said pivot-post or rivet 46 is the one end-portion of a hinge- 60 link or plate 51, the opposite end-portion of said hinge-link or plate 51 being pivotally mounted upon the said pivot-post or rivet 50. As will be evident from an inspection of said Fig. 11, in one position the edge-portion 65 52 of the link or plate 51 registers with

a rib or projection, as 53, with which the hinge-member 48 is provided, and when the position of the frame-section 41 is reversed, the opposite edge-portion 54 of the link or plate 51 registers with ribs or projections, as 70 55 and 56, with which the hinge-members 43 and 44 are provided, thus resulting in a perfect alining and registration of the said frame-section upon either side of the two main frame-sections 39 and 40, as will be 75 clearly evident.

In Figs. 12 and 13 I have shown a four-part bag-frame, consisting of an arrangement of four frame-sections, 57, 58, 59 and 60, the frame-sections 57 and 58 being 80 pivotally connected by means of the pivot-posts or rivets 61, and the frame-sections 59 and 60 being pivotally connected by means of the pivot-posts or rivets 62. Mounted upon the said pivot-posts or rivets 61 and 62, 85 in the manner of the construction described in connection with Figs. 1 to 7 inclusive, are hinge-links or plates 63 and the alining or registering links or plates 64, which co-operate with the respective frame-sections 90 to bring the frame-sections into perfect alinement or registration in the manner herein-above described.

As a further embodiment of the principles of the present invention, I have shown 95 an arrangement of two main frame-sections 65 and 66 and a third and reversible frame-section 67, respectively provided with pivot-posts or rivets 68 and 69, and pivotally connected by means of hinge-links or plates 70 100 mounted upon said pivot-posts or rivets 68 and 69. To prevent any distorted pivotal relation of the frame-section 67 with the frame-sections 65 and 66, the said main frame-sections 65 and 66 are respectively 105 provided with oppositely extending stop-plates, as 71 and 72, which may be secured to said frame-sections 65 and 66 by means of rivets 73, or may be otherwise connected therewith, as will be evident. The manner 110 of producing perfect alinement or registration of the frame-section 67 selectively with either side of the pivotally connected main frame-sections 65 and 66 will be clearly understood from an inspection of said Figs. 115 14 and 15 of the drawings, and need not therefore be further described.

I am aware that some changes may be made in the several arrangements and combinations of the various devices and parts, 120 as well as in the details of the construction of the same, as described in the foregoing specification and as defined in the claims appended to said specification, without departing from the scope of my present invention. Hence, I do not limit my present invention to the exact arrangements and combinations of the said devices and parts as set forth in the foregoing specification, 125 nor do I confine myself to the exact details 130

of the construction of the said parts as illustrated in the accompanying drawings.

I claim:—

1. In a bag-frame of the character described, a pair of main frame-sections having pintle-receiving ears, a pivot-post connecting each pair of ears at each end of said frame-sections, a third and reversibly disposed frame-section, pivot-posts at the ends 5 of said reversible frame-section, means connecting the pivot-posts of said main frame-sections with the pivot-posts of said reversible frame-section for pivotally connecting the latter with said main frame-sections, and 10 means connected with said pivot-posts and coöperating with said frame-sections for bringing said reversible frame-section into perfect alinement and registration upon either side of said pair of main frame-sections.
2. In a bag-frame of the character described, a pair of main frame-sections having pintle-receiving ears, a pivot-post connecting each pair of ears at each end of said frame-sections, a third and reversibly disposed frame-section, pivot-posts at the ends 15 of said reversible frame-section, hinge-plates connecting the pivot-posts of said main frame-sections with the pivot-posts of said reversible frame-section for pivotally connecting the latter with said main frame-sections, and means connected with said pivot-posts and coöperating with said frame-sections for bringing said reversible frame-section into perfect alinement and registration upon either side of said pair of main frame-sections.
3. In a bag-frame of the character described, a pair of main frame-sections 20 formed with angular members and having pintle-receiving ears, a pivot-post connecting each pair of ears at each end of said frame-sections, a third and reversibly dis-

posed frame-section also formed with angular members, pivot-posts at the ends of 45 said reversible frame-section, link-plates connecting the pivot-posts of said main frame-sections with the pivot posts of said reversible frame-section for pivotally connecting the latter with said main frame-sections, said link-plates being adapted to engage the ends of the angular members of the frame-sections and coöperating therewith to bring said reversible frame-section into perfect alinement and registration upon either side of said pair of main frame-sections.

4. In a bag-frame of the character described, a pair of main frame-sections formed with angular members and having 60 pintle-receiving ears, a pivot-post connecting each pair of ears at each end of said frame-sections, a third and reversibly disposed frame-section also formed with angular members, pivot-posts at the ends of 65 said reversible frame-section, link-plates connecting the pivot-posts of said main frame-sections with the pivot-posts of said reversible frame-section, said link-plates being adapted to engage the ends of the angular members of the frame-sections and coöperating therewith to bring said reversible frame-section into perfect alinement and registration upon either side of said pair of main frame-sections, and hinge-plates also 70 connected with said pivot-posts for pivotally connecting said reversible frame-section with said pair of main frame-sections.

In testimony that I claim the invention set forth above I have hereunto set my hand 80 this 13th day of April, 1917.

LUDWIG G. WIDLAK.
